SIDE BEARING

Robert B. Cottrell, Chicago, Ill., assignor to
 American Steel Foundries, Chicago, Ill., a corporation of New Jersey

Application February 17, 1939, Serial No. 256,971

22 Claims. (Cl. 267—3)

My invention relates to a shock absorbing mechanism and more particularly to an improved design of the basic idea shown and described in W. C. Drews Patent 1,958,188, issued May 8, 1934.

An object of my invention is to develop such a design of shock absorbing mechanism particularly for use as a side bearing for railway cars.

My invention further comprehends a type of side bearing which will offer smooth resistance to car body roll and prevent the development of synchronous movements of the car body.

A further object of my invention is an improved design of such a shock absorbing mechanism wherein provision is made for application of a manually operated tool by which the parts may be assembled or dismantled without other power means.

My invention also contemplates an improvement in design which permits a simpler method of assembly and at the same time accommodates the use of most suitable and efficient foundry practice.

My improved design has for a further object such construction and arrangement of parts as will prevent their loss or displacement upon failure of the arch spring associated therewith.

Other objects and details will be more apparent from the description of the associated drawings wherein Figure 1 is a top plan view of an embodiment of my novel shock absorbing device;

Figure 2 is a side elevation of the structure shown in Figure 1;

Figure 3 is an end view of the structure shown in Figures 1 and 2, the view being taken from the left as seen in those figures; and

Figure 4 is an end elevation taken from the right as seen in Figures 1 and 2;

Figure 5 is a top plan view of the base plate used in my novel structure; Figure 6 is a side elevation thereof; Figures 7 and 8 are end views thereof taken from the left and right respectively as seen in Figures 5 and 6;

Figure 9 is a longitudinal vertical section taken substantially in the plane indicated by the line 45 9—9 of Figure 5;

Figure 10 is a top plan view of the saddle casting used in my novel structure; Figure 11 is a side elevation thereof; and Figure 12 is an end elevation taken from the left as seen in Figure 10;

Figure 13 is a sectional view taken in the longitudinal vertical plane substantially bisecting the saddle casting as indicated by the line 13—13 of Figure 10;

Figure 14 is a top plan view of my novel form 55

of truss spring; Figure 15 is a side elevation thereof; and Figure 16 an end elevation; and

Figure 17 is a side elevation, partly in section, of my novel side bearing showing the method of assembly thereof.

My novel device comprises a base plate generally indicated at 2, having at its ends securing lugs 4 and 5 with the central openings 6, 6 therein for reception of securing bolts or studs. In the modification shown I have arranged said securing lugs at the ends of the base plate, but in other modifications I may place said securing lugs at the opposite sides of the base plate instead of at the ends. At the juncture of said lug 4 with the main body of the base plate are formed the reinforcing gussets or ribs 8, 8, the inner edges of said ribs 8 merging with the end wall 10 arcuately relieved on its inner face to form a shallow transverse channel as indicated at 12 (Figure 9), thus making a seat or abutment for one end of the arch spring 14.

The bottom of the base plate is cored out over a large portion of its surface as indicated at 16, 18, 20 and 22 to reduce the weight of the casting 25 and to limit the area required to be finished to relatively narrow bands about the perimeter of the casting and bridges there-across as indicated at 24, 26 and 28. This is particularly desirable since the surface on which the base plate is seated is required to be smooth and true, and by so arranging the bottom of the plate any necessary machining is reduced to a minimum.

Merging with the end wall 10 are the short lateral walls 30, 30 at opposite sides of the casting, said side walls having the cored out openings 32, 32 for reception of the hook-like ends 34, 34 of the truss springs 36, 36. The form of the openings 32 is best seen from the side views of Figures 2 and 6 and their inner edges are defined by the post-like terminations 35 (Figure 6). The walls 30 in conjunction with the studs or posts 35 serve as retaining means for the truss springs 36, the hook-like ends of which have engagement as at 38 with the post-like structures 35. Centrally of the casting and at opposite sides thereof are formed the studs 40, 40 having top surfaces of arcuate form as indicated at 42 (Figure 6), said surfaces providing limiting stops for the flexing of the arch spring 14 when placed under load. 50 The said studs 40, 40 have the reinforcing end flanges 44, 44 merging with the base plate.

The opposite end of the arch spring 14 is seated in the shallow transverse channel 48 (Figure 13) formed on the end wall 49 of the saddle casting generally indicated at 50, said saddle

casting being shown in detail in Figures 10 to 13 inclusive and having the lateral guide and retaining flanges 52, 52 received in the channel guide ways 54, 54 (Figure 3) formed in the flanged and re-flanged retaining ears 56, 56 provided at opposite sides adjacent the end of the base plate 2. The end wall 49 of the saddle casting is recessed centrally thereof to form the tool pocket 51 (Figure 10) hereafter referred to.

The saddle casting 50 has the lateral walls 58, 58 in which are formed the openings 60, 60 for reception of the opposite ends of the truss spring, said openings having their outer extremities limited by the flaring flanges 62, 62 (Figure 11) for the purpose already described. The openings 60 are defined at their inner edges by the post-like structures indicated at 64, 64 having a cross section with arcuate surfaces at 66, 66 forming seats for the hook ends of the truss springs.

The arch spring 14 is a steel spring plate formed with the desired arch and with ends having rounded edges formed with smooth radii for complementary abutment with the seats 12 and 48 already described.

The truss spring 36 shown in Figures 14 to 16, inclusive, is formed of round bar spring steel stock with the central portion 68 of uniform curvature with the end portions 72, 72, said end portions terminating in hook-like structures indicated at 74, 74 upon the inner faces of which are formed the arcuate surfaces 76, 76 complementary in form to the already described surfaces 38 and 66 against which they are seated.

In assembly a saddle casting is mounted on the base plate by sliding the flanges 52 into the slots 54 from the inner ends of said slots, the movement thereof being limited by abutment of the stops 88, 88 (Figure 1) on the side walls of the saddle casting against the inner edges of the retaining ears 56, 56. Thereafter, the truss springs 36, 36 are inserted one after the other and power means may be applied to stress said truss springs and thus permit the insertion of the arch spring 14. In place of power means a hand tool 90 formed with the toe 92 and the heel 94 may be inserted in the pocket 51 and used to flex the assembled arch spring 14 and, at the same time, flex the truss springs 36, 36 in the manner shown in Figure 17, the tool 90 being moved to the position shown at 90A, after which the end of the arch spring 14 in abutment with the tool 90 under the heel 94 thereof will slide, or may be forced, downwardly into the seat 48 of the saddle casting 50.

In operation, application of a load upon the arch spring 14 will tend to move the saddle casting outwardly along the base plate and this movement will be resisted by the truss springs 36, 36. As assembled, both the arch spring 14 and the truss springs 36, 36 are under strain and the amount and character of this strain may be controlled accurately depending upon the service in which the device is to be used. In other words, the capacity may be relatively large or relatively small.

It will be noted that in my novel arrangement I have so designed the parts that if the arch spring be lost or destroyed the other parts will be retained in assembly and may be re-used with a new arch spring.

It is to be understood that I do not wish to be limited by the exact embodiments of the device shown which are merely by way of illustration and not limitation as various and other forms

of the device will, of course, be apparent to those skilled in the art without departing from the spirit of the invention or the scope of the claims.

I claim:

1. A shock absorber comprising a substantially flat base plate, an integral transverse abutment adjacent one end of said plate, vertical shoulders adjacent opposite ends of said abutment, a slidable transverse abutment supported on said plate adjacent the opposite end thereof, vertical shoulders integrally formed with said slidable abutment, truss springs supported on said plate and having their opposite ends in engagement with the shoulders associated with said abutments respectively, an arch spring flexed between and serving to spread said abutments and to flex said truss springs, and means on said plate and on said sliding abutment serving to limit the relative movement therebetween and to retain said parts in assembly in case of loss or breakage of said arch spring, said means comprising lateral flanges on said sliding abutment, shoulders on said last mentioned abutment inwardly of said flanges, and channels on said base plate receiving said lateral flanges and having walls engageable with said shoulders.

2. In a shock absorber, a base plate having adjacent one end a fixed transverse abutment and supporting adjacent the opposite end a slidable transverse abutment, a plate spring flexed between said abutments to urge them apart, stop means at opposite sides of said base adjacent the center thereof limiting the flexure of said plate spring, truss springs supported at their opposite ends from said base plate and said slidable abutment respectively and operative to resist the action of said plate spring, and flanged and re-flanged retaining means on said base plate forming channels, said sliding abutment having lateral flanges received in said channels and means on said base plate engaging said flanges to limit the relative sliding movement therebetween and retain said parts in assembled relationship.

3. A shock absorber comprising a substantially flat base plate, an integral transverse abutment adjacent one end of said plate, vertical shoulders adjacent opposite ends of said abutment, a slidable transverse abutment supported on said plate adjacent the opposite end thereof, vertical shoulders integrally formed with said slidable abutment, truss springs supported on said plate and having their opposite ends in engagement with the shoulders associated with said abutments respectively, an arch spring flexed between and serving to spread said abutments and to flex said truss springs, and means on said plate and on said sliding abutment serving to limit the relative movement therebetween and to retain said parts in assembly in case of loss or breakage of said arch spring.

4. In a shock absorber, a base plate having at one end a transverse abutment with adjacent vertical shoulders, flanged and re-flanged portions forming opposed longitudinal lateral channels adjacent the opposite end of said plate, a slidable transverse abutment having lateral flanges received in said channels and adjacent vertical shoulders, truss springs having their opposite ends in engagement with the respective shoulders at opposite ends of the device and flexed therebetween, and an arch spring flexed between said abutments to urge them apart, whereby application of a load to said arch spring serves to spread said abutments and said spread is resisted by said truss springs.

5. In a shock absorber, a base plate having at one end a transverse abutment with adjacent shoulders, flanged and re-flanged portions forming opposed longitudinal lateral channels, adjacent the opposite end of said plate, a slideable transverse abutment having lateral flanges received in said channels and adjacent shoulders, truss springs having their opposite ends in engagement with the respective shoulders at opposite ends of the device and flexed therebetween, and an arch spring flexed between said abutments to urge them apart and resist said truss springs, whereby an equilibrium of forces is established between said arch spring and said truss springs.

6. In a shock absorber, a base plate having adjacent one end a transverse abutment with spaced vertical shoulders, a sliding transverse abutment mounted on said plate adjacent the opposite end, spaced shoulders on said sliding abutment, a truss spring assembly supported on said plate centrally thereof and comprising a plurality of springs having their opposite ends engaging said shoulders adjacent said respective abutments, an arch spring flexed between said abutments and operative to spread them apart and to flex said truss springs, and means on said plate and said slideable abutment serving to retain them in assembled relationship if said arch spring is broken.

7. In a shock absorber, a base plate having adjacent one end a fixed transverse abutment and supporting adjacent the opposite end a slideable transverse abutment, a plate spring flexed between said abutments to urge them apart, stop means at opposite sides of said base adjacent the center thereof limiting the flexure of said plate spring, and truss springs supported at their opposite ends from said base plate and said slideable abutment respectively and operative to resist the action of said plate spring, said slideable abutment having a tool pocket adjacent the end of said plate spring adapted to receive a flexing tool.

8. In a shock absorber, a base plate, a fixed abutment on said plate adjacent one end, a sliding abutment on said base plate adjacent the opposite end, a flat arch spring flexed between said abutments to urge them apart, and truss springs supported on said plate beneath said arch spring and having their opposite ends engaging means on said plate and means on said sliding abutment respectively to resist the action of said arch spring, said sliding abutment having lateral flanges and lateral abutments adjacent said flanges, and said base plate having portions flanged and re-flanged to form guide ways and abutments for said flanges.

9. A shock absorber comprising a substantially flat base plate, an integral transverse abutment adjacent one end of said plate, vertical shoulders adjacent opposite ends of said abutment, a slideable transverse abutment supported on said plate adjacent the opposite end of said plate, vertical shoulders integrally formed with said slideable abutment, truss springs supported on said plate and having their opposite ends in engagement with the shoulders associated with said abutments respectively, and an arch spring flexed between and serving to spread said abutments and to flex said truss springs.

10. A shock absorber comprising a base plate, a pair of abutments supported thereon and having sliding relation with respect to each other, spaced stop means supported in fixed relation-

ship to said abutments respectively, truss springs flexed between stop means associated with said abutments respectively and an arch spring flexed between said abutments to resist the action of said truss springs, and interengaging means on said plate and said sliding abutment retaining said parts in assembled relationship and limiting their relative movement.

11. In a shock absorber, a base plate, a fixed abutment on said plate adjacent one end, a sliding abutment on said base plate adjacent the opposite end, a flat arch spring flexed between said abutments to urge them apart, truss springs supported on said plate beneath said arch spring and having their opposite ends engaging means on said plate and means on said sliding abutment respectively to resist the action of said arch spring, and abutment means formed at the opposite sides of said plate laterally thereof to limit the flexure of said arch spring.

12. In a shock absorber, a base plate having at one end a transverse abutment with vertical shoulders at opposite ends of said abutment, flanged and re-flanged portions forming opposed longitudinal lateral channels adjacent the opposite ends of said plate, a slideable transverse abutment having lateral flanges received in said channels and adjacent shoulders, truss springs having their opposite ends in engagement with the respective shoulders at opposite ends of the device and flexed therebetween, and an arch spring flexed between said abutments to urge them apart and resist said truss springs.

13. In a shock absorber, a base plate having adjacent one end a transverse abutment with spaced vertical shoulders, a sliding transverse abutment mounted on said plate adjacent the opposite end, spaced shoulders on said sliding abutment, a truss spring assembly supported on said plate centrally thereof and comprising a plurality of springs having their opposite ends engaging the shoulders adjacent said respective abutments, and an arch spring overlying said assembly and flexed between said abutments and operative to spread them apart and to flex said truss springs opposing said spread.

14. In a shock absorber, a base plate, fixed and slidably movable abutments supported thereon, a plate spring flexed between certain abutments to urge them apart, other resilient means between said plate and said spring engaging means on said abutments respectively to resist the action of said spring, and means on said movable abutment engaging means on said base plate to retain said parts in assembled relationship and to limit said sliding movement.

15. In a shock absorber, a base plate, a fixed abutment on said plate adjacent one end, a sliding abutment on said base plate adjacent the opposite end, a flat arch spring flexed between said abutments to urge them apart, and truss springs supported on said plate beneath said arch spring and having their opposite ends engaging means on said plate and means on said sliding abutment respectively to resist the action of said arch spring.

16. A shock absorber comprising a base plate, integral and slideable abutments supported thereon, a plate spring flexed between said abutments, and resilient means supported on said plate beneath said spring in engagement with said slideable abutment to resist the spreading movement set up by said plate spring, said slideable abutment having a pocket adapted to receive a flexing tool.

17. In a shock absorber, a base plate, fixed and slidable abutments supported thereon, a spring flexed between certain abutments to urge them apart, other resilient means between said plate and said spring engaging means on said abutments respectively to resist the action of said spring, and a pocket on said slidable abutment adapted to receive a tool for flexing said spring.

18. A shock absorber comprising a base plate, integral and slidable abutments supported thereon, a flexed plate spring having its ends seated against said abutments, and resilient means supported on said plate beneath said spring in engagement with said slidable abutment to resist the spreading movement set up by said spring.

19. A shock absorber comprising a base plate, integral and slidable abutments supported thereon, a plate spring flexed between said abutments, and resilient means supported on said plate beneath said spring in engagement with said slid- 20
able abutment to resist the spreading movement set up by said plate spring, said resilient means comprising a plurality of members of arcuate form and uniform curvature end to end, each of said members having adjacent its opposite ends on the inner faces thereof relatively shallow cavities affording seats for means on said abutments respectively.

20. In a shock absorber, a base plate, fixed and slidable abutments thereon having stop 30

means, a spring flexed between said abutments to urge them apart, other resilient members between said plate and said spring engaging said stop means respectively to resist the action of said spring, each of said resilient members having an arcuate form of regular curvature interrupted on its inner faces adjacent its opposite ends by a relatively shallow concave seat forming a means of engagement with said stop means.

21. In an arcuate resilient member formed of round bar stock of substantially constant curvature and section from end to end, arcuate end portions of similar form, each of said end portions having a shallow cavity forming a concave seat on the inner face thereof for abutment with means for flexing said member, the outer face of said member being uninterrupted, and said shallow cavities reducing to a minimum concentration of stresses at said end portions.

22. An arcuate resilient member of substantially uniform section end to end formed of round bar stock, said uniform section being slightly diminished adjacent the ends thereof to afford shallow cavities on the inner face of said member for abutment with associated flexing means, the outer face of said member being of unbroken uniform curvature, and said shallow cavities reducing to a minimum concentration of stresses at said ends.

ROBERT B. COTTRELL.
